(57) **CLAIM**

The ornamental design for a magnetizer as shown and described.

DESCRIPTION

FIG. 1 is a perspective view of a magnetizer, showing the new design;

FIG. 2 is a front view of the magnetizer of FIG. 1;

FIG. 3 is a rear view of the magnetizer of FIG. 1;

FIG. 4 is a left side view of the magnetizer of FIG. 1;

FIG. 5 is a right side view of the magnetizer of FIG. 1;

FIG. 6 is a top plan view of the magnetizer of FIG. 1; and,
FIG. 7 is a bottom plan view of the magnetizer of FIG. 1.
The broken lines depict portions of the magnetizer in which
the design is embodied that form no part of the claimed
design.
